UNITED STATES PATENT OFFICE.

ARTHUR R. MOSLER, OF NEW YORK, N. Y.

SPARK-PLUG.

1,321,467.

Specification of Letters Patent. Patented Nov. 11, 1919.

Application filed January 16, 1918. Serial No. 212,129.

To all whom it may concern:

Be it known that I, ARTHUR R. MOSLER, a citizen of the United States, and resident of the borough of Manhattan, in the city 5 and State of New York, have invented a new and useful Improvement in Spark-Plugs, of which the following is a specification.

The object of my invention is to provide 10 certain improvements in spark plugs, whereby the parts may be very readily assembled, the insulating block being locked against removal from the shell by a locking ring, the locking ring serving not only to secure 15 the block within the shell but also serving to force the block onto its seat.

A further object is to provide novel means for packing the insulating block.

A practical embodiment of my invention 20 is represented in the accompanying drawings, in which—

Figure 1 represents my improved spark plug in top plan,

Fig. 2 is a longitudinal central section 25 through the plug, the insulating block and its electrode being shown in side elevation, and

Fig. 3 is a cross section taken in the plane of the line III—III of Fig. 2.

30 The spark plug shell 1 has a smaller bore 2 and a larger bore 3 between which is formed a flaring seat 4. The insulating block has reduced inner and outer ends 5, 6, and an enlarged intermediate portion 7 35 forming inner and outer shoulders 8, 9, the inner shoulder 8 opposite the shell seat 4, being tapered. The outer shoulder 9 is also tapered.

The outer end of the shell is provided 40 with an interior annular groove 10 having one or both of its walls 11 arranged at right angles to the longitudinal axis of the plug.

A normally contracted yielding locking ring 12 is partly seated in the groove 10 and 45 is partly located within the larger bore 3 of the shell opposite the tapered shoulder 9 of the insulating block.

The groove 10 is sufficiently deep to permit the ring 12 to be expanded into the same 50 as the block is inserted into the shell.

As soon as the block is inserted sufficiently, the ring 12 will contract against the tapered shoulder 9 of the block and thereby force the block onto its seat 4. A

soft metal gasket 13 and a spring metal 55 washer 14 are interposed between the shoulder 9 of the insulating block and the locking ring 12. A soft metal gasket 15 is interposed between the shell seat 4 and the insulating block shoulder 8. The gasket 13 is 60 preferably made of soft copper wire and the gasket 15 is preferably a coil of soft copper wire. In forcing the block into position within the shell, the gaskets will be flattened to secure a tight joint, which pressure 65 is maintained by the action of the locking ring 12.

Preferably a lead or other readily fusible metal wire coil 16 is inserted in the space 70 between the insulating block and shell, it being intended that this wire packing should melt at the high temperatures to which the spark plug is subjected in use and the molten metal flow into the gasket 15 and combine therewith to insure a gas-tight 75 joint at this point.

From the above description, it will be seen that I have provided a very simple and effective means for permanently securing the insulating block within the shell and 80 that I have provided a very effective packing between the block and shell.

It is evident that changes may be resorted to in the form, construction and arrangement of the several parts without departing 85 from the spirit and scope of my invention; hence I do not wish to limit myself strictly to the structure herein set forth, but

What I claim is:

1. A spark plug comprising an insulating block, a shell and yielding means permitting the insertion of but preventing the removal of the block from the shell, said means serving to force the block onto its seat. 90

2. A spark plug comprising an insulating block, a shell and a yielding locking ring permitting the insertion but preventing the removal of the block from the shell, said ring serving to force the block onto its seat. 95 100

3. A spark plug comprising an insulating block, a shell and a normally contracted yielding locking ring permitting the insertion but preventing the removal of the block from the shell. 105

4. A spark plug comprising an insulating block, a shell and a normally contracted yielding locking ring permitting the in-

sertion but preventing the removal of the block from the shell, said ring serving to force the block onto its seat.

5. A spark plug comprising a shell having a seat, an insulating block having a shoulder, a soft metal gasket interposed directly between said seat and shoulder, and a fusible metal packing interposed directly between the shell and block.

10 6. A spark plug comprising a shell having a seat, an insulating block having a shoulder, a soft metal gasket interposed directly between said seat and shoulder, and yielding means interlocked with the block 15 and shell for securing the block within the shell and forcing it onto its seat.

7. A spark plug comprising a shell having a seat, an insulating block having a shoulder, a soft metal gasket interposed directly between said seat and shoulder, a fusible metal packing interposed directly 20 between the shell and block, and yielding

means interlocked with the block and shell for securing the block within the shell and forcing it onto its seat.

25 8. A spark plug comprising an insulating block having a tapered shoulder, a shell having an internal annular recess with a wall at right angles to the longitudinal axis of the block and a normally contracted locking ring located partly within said recess, and exerting pressure on said tapered shoulder of the block to force it onto its seat.

30 9. A spark plug comprising a shell having a seat, an insulating block having a shoulder, a copper wire coil gasket interposed between said seat and shoulder and a readily fusible lead wire coil interposed between the shell and block.

35 In testimony, that I claim the foregoing as my invention, I have signed my name this 11th day of December, 1917.

40 ARTHUR R. MOSLER.
